UNITED STATES PATENT OFFICE.

JOHN H. SMITH, OF FAIRCHILD, WISCONSIN.

SHOE-BUCKLE.

SPECIFICATION forming part of Letters Patent No. 462,779, dated November 10, 1891.

Application filed June 24, 1891. Serial No. 397,298. (No model.)

To all whom it may concern:

Be it known that I, JOHN H. SMITH, a citizen of the United States, residing at Fairchild, in the county of Eau Claire and State of Wisconsin, have invented certain new and useful Improvements in Shoe-Buckles; and I do hereby declare that the following is a full, clear, and exact description of the same, reference being had to the annexed drawings, making a part 10 of this specification, and to the letters of reference marked thereon.

Figure 1 of the drawings represents a top plan view of my improved shoe-buckle, showing the two sections thereof separated; Fig. 15 2, a similar view showing the two sections connected together; Fig. 3, a longitudinal central section of Fig. 2; Fig. 4, a detail view in perspective of the section constituting the tongue.

20 The present invention has for its object to provide a shoe-buckle simple in construction, possessing the required strength and durability, capable of ready adjustment, and forming a perfect and secure fastening for the 25 shoe, which objects I attain by the construction substantially as shown in the drawings, and hereinafter described and claimed.

In the accompanying drawings, A B represent the two sections of the buckle, the former 30 constituting the tongue thereof and the latter the keeper, and are provided with loops a at their outer ends to serve as means for attaching them to the shoe by sewing or by any other preferred and well-known means.

35 The section of the buckle which I term the "keeper," as indicated at B, is formed from a blank of sheet metal stamped out in the usual manner, forming the loop a, as herein-before referred to, and a central line of slots 40 b, as shown more clearly in Fig. 1. The rectangular blank from which this keeper is formed is of sufficient width to admit its edges being turned over to form guides c upon each side of the line of slots above described. 45 These "flanged guides," as I shall term them, are for the purpose of guiding the tongue A and retaining it against the keeper B, and also to take off any lateral pressure upon the slots, and also materially adds to the strength 50 and rigidity of the keeper.

The tongue A is formed with an elongated opening d, which extends lengthwise thereof and has located over it a flat spring C, said spring being riveted or otherwise suitably attached at one end to the tongue. The free 55 end of the spring C is turned over upon itself to form a double thickness, and is curved, as shown, to present a thumb-piece e to take hold of when it is desired to raise the free end of the spring in disconnecting or adjusting 60 the two sections of the buckle, the double thickness of metal forming a more rigid and much stronger thumb-piece than would be otherwise.

Upon the under side of the spring C near 65 its free end is a catch f, which has a beveled heel g, so as to admit of its freely passing over the line of slots b when it is desired to bring the two sections of the buckle nearer together in tightening the shoe; but the 70 straight side of the catch, when in engagement with any one of the slots, will hold the tongue in position on the keeper. The turned-over end of the spring to form the thumb-piece is riveted, as shown at h, and the catch 75 f is formed with a shank i to serve as a rivet in securing it to the spring at the end which forms the thumb-piece.

The two sections forming the buckle, which I have designated the "tongue" and "keeper," 80 respectively, are curved on an arc of a circle, as shown in Fig. 3, as is common with this class of buckles, and any changes in the several details of construction that would come within ordinary mechanical skill I reserve the right 85 to make without departing from the principle of my invention.

A shoe-buckle constructed as herein described is not only both strong and durable, but is inexpensive, and can be manufactured 90 and placed upon the market at a comparatively small cost, and its simplicity of construction and ease of operation materially enhances the value of shoes to which such buckle is attached.

Having now fully described my invention, 95 what I claim as new, and desire to secure by Letters Patent, is—

In a shoe-buckle, a keeper having flanged guides upon its sides and a plurality of slots, 100

in combination with a slotted tongue and a flat spring connected thereto and located over the slot, the free end of the spring having a catch to engage with the slots in the keeper, 5 and a thumb-piece for raising said spring, substantially as and for the purpose set forth. In testimony that I claim the above I have

hereunto subscribed my name in the presence of two witnesses.

JOHN H. SMITH.
